Glendale, Calif. 91206

Filed Aug. 25, 1969, Ser. No. 18,840

Term of patent 14 years

Int. Cl. D22—08

U.S. Cl. D22—25

FIG. 1 is a top plan view of the fishing reel and handle combination;

FIG. 2 is a side elevational view thereof;

FIG. 3 is a bottom plan view thereof;

FIG. 4 is a sectional view taken along line 4—4 of FIG. 1;

FIG. 5 is a perspective view taken from the bottom of FIG. 2; and

FIG. 6 is a perspective view taken from the top of FIG. 2.

The fishing reel and handle combination is characterized by two closely spaced external flanges adjacent an open front end of the combination giving the combination the appearance of a tunnel with two collars near its mouth.

I claim:

The ornamental design for a fishing reel and handle combination, as shown and described.
